UNITED STATES PATENT OFFICE

2,534,143

CENTRIFUGALLY ACTIVATED CIRCUIT
CHANGING MECHANISMChester S. Phillips, St. Louis, Mo., assignor to
The Emerson Electric Manufacturing Company, St. Louis, Mo., a corporation of Missouri

Application July 5, 1947, Serial No. 759,073

9 Claims. (Cl. 172—279)

1

This invention relates to improvements in centrifugally actuated circuit changing mechanism of the type particularly adapted to short circuit the windings of motors having a repulsion start and an induction operating characteristic.

An object of the invention is to provide a compact, quick, positive and uniformly acting mechanism for the purpose of converting from a repulsion starting operation to an induction running operation and the reverse, for embodiment in a repulsion-induction motor.

Another more specific object of the invention is to provide a mechanism of the type stated in which the action above mentioned is effected by making and breaking contact with all commutator bars of the armature suddenly and simultaneously when an adjustable predetermined motor speed has been attained, and thereby minimize sparking during the change from the one operation of the motor to the other.

A general object of the invention is to simplify mechanism of the character mentioned and to provide an efficient operating structure that is economical in construction and which may be installed with facility in motors of the type referred to.

Other objects of the invention will appear from the following detailed description thereof taken in connection with the accompanying drawing, in which:

Fig. 1 is a vertical longitudinal section taken substantially on the line 1—1 of Fig. 2;

Fig. 2 is a vertical cross section taken substantially on the line 2—2 of Fig. 1;

Fig. 3 is a fragmentary plan view, showing a part of the commutator and of the circuit-change mechanism;

Fig. 4 is a fragmentary longitudinal sectional view showing a part of the commutator and of the circuit-change mechanism, with the latter in short-circuiting position;

Fig. 5 is an enlarged vertical fragmentary section of the retaining discs for the short-circuiting segments, one of the segments being shown in side elevation;

Fig. 6 is an isometric view of one of the weight units and two of the associated links; and

Fig. 7 is an isometric view of one of the short-circuiting segments removed from the assembly.

In the embodiment of the invention selected for illustration, the structure is shown in association with standard motor parts. It will be understood that the motor windings are such that, during the starting period, the motor is designed to operate with a repulsion characteristic by current shunted through brushes (not shown),

2

which contact the horizontal surface of the commutator bars; and that, by short circuiting the vertical faces of the commutator bars, the motor winding permits the conversion from repulsion operation to induction operation, as will be readily understood.

By reference, therefore, to the drawing, it will be understood that a motor of this type includes a motor shaft 10 upon which a commutator 11 having an annular series of commutator bars 12 is mounted. The bars are assembled as usual in an annular series to provide a horizontal peripheral surface which the brushes contact to complete the circuit during the repulsion operation of the motor. The bars also form an annulus at the inner end thereof providing a vertical contact surface which, in cooperation with movable contacting segments, operate to short circuit the commutator bars and thereby convert the motor for an induction operation during the running period of the motor.

It will be understood that the commutator is affixed to the motor shaft, as shown by a pin 14 that passes through the shaft and the hub of the commutator shell. These elements together comprise the armature assembly of the motor and are standard, as will be well recognized. They are illustrated merely for the purpose of disclosing the manner in which the mechanism of the present invention is assembled and associated therewith.

The mechanism of the present invention includes a sleeve 15 that is fitted over the shaft 10. A contact assembly carrier, comprising an inner annular disc 16 and an outer annular disc 17, is mounted over the sleeve 15. The disc 16, at its periphery, is formed to provide a U-shaped recess 18 and the disc 17 is extended beyond the periphery of the disc 16, forming a pocket in which an annular series of contact segments 20 are mounted. The contact segments are in the form best shown in Figs. 5 and 7, and include an upper rectangular section with an integral tail piece 21 providing a recess 19 into which the peripheral margin or flange 50 of the plate 16 extends. The outer walls of the members 20 are held in position by the marginal extremity of the disc 17.

The contact segments are assembled in an annular series in their carrier and support, and the two discs 16 and 17 are spot welded, as at a (Fig. 5), or otherwise secured at their matching parallel faces, so that the annular series of contact segments is free to move circumferentially.

Outwardly from the outer face of the disc 17 is an annular plate 22 likewise fitting over the sleeve 15 and assembled in abutment with the

outer face of the disc 17. The plate 22 is provided with six pairs of ears 23, arranged in groups of two pairs, one radially outside of the other, and the groups spaced circumferentially at angles of 120°. Each group of these ears may be deformed from the plate, leaving an opening 28 on the edges on which the ears appear.

The plate 22 is provided with an axial hub 24, which is mounted over the external wall of the sleeve 15 and is longitudinally slidable thereon. The diameters of the axial openings in the discs 16 and 17 are slightly in excess of the external diameter of the hub 24, and the discs, therefore, mount over and surround the outer periphery of said hub 24.

A second annular plate 25 having a hub 26 is likewise mounted over and carried by the sleeve 15. The hub flange 26 of the plate 25 is affixed to the sleeve 15 by welding, or by other suitable securing means, and, therefore, is not longitudinally movable in respect to the sleeve. Furthermore, the sleeve 15 and the hub 26 are fixedly secured to the shaft 10 by a pin 40 that extends through these members.

The plate 25 is provided with six pairs of ears 27 that extend forwardly from the front face thereof, and are arranged in three groups of two pairs of each group, in the same manner in respect of the plate 25 as the ears 23 are arranged in respect of the plate 22, each group of four ears being disposed at the edges of an opening 28.

Three weight assemblies are designed to be pivotally mounted between the plate 22 and the plate 25. The weight assembly construction is illustrated particularly in Fig. 6, from which it will be understood that each includes a rectangular weight member 30 pivotally connected to a pair of toggle links, each link being in the form as shown in Fig. 6 and each including a right and left link bar 31 spaced apart and transversely connected by a web 32.

A pin 33 constitutes a common pivot for the inner ends of the links 31 and the weight member 30, said pin passing through the inner extremities of said link bars and transversely through an upper section of the weight member. The outer extremities of each of the link bars 31 are connected, respectively, with the ears 23 and the ears 27 by pivot pins 34, the outer ends of the forward pairs of links extending through the openings 28, as best illustrated in Figs. 1 and 4 of the drawing. There are two pairs of the links connected with radial spacing, to each weight member 30, to maintain the weights radial during their movement.

The vertical inner faces of the series of contact segments 29 are normally retracted from the vertical faces of the commutator bars 12 by means of an expansion spring 35 coiled about the shaft 10 and bearing at its outer extremity against a flanged collar 36 encompassing the shaft 10. The outer face of the flange of said collar abuts against the face of the hub of the commutator shell. The spring, at its opposite end, bears against the axial margin of the disc 16 and overlies the outer margin of the hub flange 24 of the annular plate 22.

The mechanical advantage of the toggle links increases as the weights move outwardly; and also, as the weights move outwardly, their rotative speed increases. Consequently, when sufficient speed is attained to start the weights outwardly, they continue to move with increasing centrifugal speed, and close the short-circuiting segments

against the commutator bars with a snap action. In their outer positions, the weights act with maximum force, and the toggle links act with maximum advantage, so that the short-circuiting segments are held forcibly against the commutator bars. The toggle links are short of dead center in the outer position, but are preferably near dead center.

When the speed decreases to a point where the centrifugal force of the weights acting through the spread toggle links is no longer able to overcome the spring 35, the spring will collapse the toggle links, forcing the weights in. As the weights move inward from operating position, their centrifugal force and the mechanical advantage of the links decreases rapidly, and the weights move in rapidly, giving a snap-action break of the short-circuiting segments from the commutator bars.

Since the protracted movement is due to the weighted toggle links equi-circumferentially spaced, and the toggle links are arranged in parallel pairs in each group, the two plates or discs 17 and 25 are maintained parallel, overcoming any lag in an individual radial movement of any one of the weights. Hence the circumferential contact between the contact segments and the vertical faces of the commutator bars is uniformly and substantially simultaneously effected.

This mechanism is readily made and assembled in place. The short-circuiter sub-assemblies are formed by spot welding together the two discs 16 and 17 with their segments 29 between them. The centrifugal weight assemblies are pre-assembled by welding the plate 25 to the sleeve 15, sliding the plate 22 over the sleeve, pinning the links in place, and pinning the several weights to the links.

The retainer ring 36 is slid onto the shaft 10 into abutting relationship with the commutator, as shown. The coil spring 35 is then put over the shaft. The short-circuiter sub-assembly is put over the shaft against the spring. The weight sub-assembly on the sleeve 15 is fitted over the shaft, and finally the pin 40 is secured in place to hold all of the parts together.

The construction, as appears from the foregoing, leads to convenient and inexpensive manufacture, sub-assembly and final assembly.

From the foregoing description, it will be understood that the invention fully accomplishes the purposes hereinbefore set out, and that, while I have illustrated a specific embodiment and have particularly described the details of the construction, it is not to be understood that the invention is limited except as defined by the claims.

What is claimed is:

1. In a centrifugal actuator for mounting on a rotary shaft, a first member mounted on the shaft for rotation therewith, a second member mounted for axial movement relatively to the shaft, a centrifugal weight, a pair of parallel links pivotally connecting the weight with the second member, the links of the pair being disposed at different distances from the axis of the shaft to determine the path of movement of the weight relatively to the second member, and link means pivoting the weight to the first member.

2. In a centrifugal actuator for mounting on a rotary shaft, a first member mounted on the shaft for rotation therewith, a second member mounted for axial movement relatively to the shaft, a centrifugal weight, a pair of parallel links pivotally connecting the weight with the

second member, and link means pivoting the weight to the first member, said link means likewise comprising a pair of parallel links pivoted to the weight and to the first member, the links of each pair being at different distances from the axis of the shaft to fix the path of movement of the weight relatively to the second member.

3. In a centrifugal actuator for mounting on a rotary shaft, a first member mounted on the shaft for rotation therewith, a second member mounted for axial movement relatively to the shaft, a centrifugal weight, a pair of parallel links pivotally connecting the weight with the second member, the links being disposed in a plane radial to the axis of the shaft, and link means pivoting the weight to the first member, said link means likewise comprising a pair of parallel links pivoted to the weight and to the first member, the two pairs of links having common pivots on the weight, there being one pivot connecting the two radially inward links, and one pivot connecting the two radially outward links with the weight.

4. In a centrifugal actuator for mounting on a rotary shaft, a first member mounted on the shaft for rotation therewith, a second member mounted for axial movement relatively to the shaft, a plurality of at least three centrifugal weights arranged in spaced relation around the shaft, a pair of parallel links for each weight, the links of each pair being arranged at different distances from the axis of the shaft, and each pivoted to the weight and to the second member, and link means connecting each of the weights pivotally to the first member.

5. In a centrifugal actuator for mounting on a rotary shaft, a first member mounted on the shaft for rotation therewith, a second member mounted for axial movement relatively to the shaft, a plurality of at least three centrifugal weights arranged in spaced relation around the shaft, a pair of parallel links for each weight, the links of the pair being arranged at different distances from the axis of the shaft, and each pivoted to the weight and to the second member, and link means connecting each of the weights pivotally to the first member, said link means comprising a pair of parallel links for each weight, pivoted thereto and to the first member, the links of the latter pair being likewise arranged at different distances from the axis of the shaft.

6. In a centrifugal actuator for mounting on a rotary shaft, a first member mounted on the shaft for rotation therewith, a second member mounted for axial movement relatively to the shaft, a centrifugal weight, a pair of parallel links pivotally connecting the weight with the second member, a second pair of parallel links pivoting the weight to the first member, said second member comprising a disc-like element, a short-circuiting device including a disc-like assembly, and means yieldably urging the short circuiting device toward the second member.

7. In a centrifugal actuator for mounting on a rotary shaft, a first member mounted on the shaft for rotation therewith, a second member mounted for axial movement relatively to the shaft, a centrifugal weight, a pair of parallel links pivotally connecting the weight with the second member, the links being disposed at different distances from the axis of the shaft, and link means pivoting the weight to the first member, said link means likewise comprising a pair of parallel links pivoted to the weight and to the first member, the links of the latter pair being at

5 different distances from the axis of the shaft, the links being arranged in a toggle manner wherein, when the weight is toward the axis, the links between the weight and the second member extend from the weight angularly outward, and when the weight is moved outwardly, the links approach parallelism to the said axis, an axially movable actuated device, yieldable means urging it axially toward the second member, said actuated device being adapted to be moved by the centrifugal movement of the weights to a position short of that in which the links are parallel to the axis of rotation.

10 15 20 25 30 35 40 45 50 55 60 65 70 75

8. In a centrifugal short-circuiting mechanism for an electric motor having a shaft and commutator elements having contact faces disposed annularly about the shaft, a short-circuiting device sub-assembly including a pair of discs having holes to receive the shaft, and attached together face to face, said discs being shaped to provide a peripheral groove with a retaining edge, a plurality of commutator segments in the groove and retained by the edge, but peripherally slidable in the groove, a spring surrounding the shaft and engaging the said sub-assembly and arranged to urge the sub-assembly away from the commutator elements, a centrifugal actuator sub-assembly including a first and a second disc-like actuator member having shaft receiving holes, a sleeve fixed to the first actuator member, a plurality of centrifugal weights spaced about the axis of the shaft, link means pivoting the weights to the two actuator members, this actuator sub-assembly being fittable over the shaft with the second actuator member engaging the short-circuiting device sub-assembly opposite the spring, and means attaching the first actuator member to the shaft.

9. In a centrifugal actuator, a sleeve adapted to fit over a shaft, a first radial member attached to the sleeve and extending outwardly therefrom to provide at least three points of connection spaced around the shaft, a second radial member slidably mounted over the sleeve, and extending outwardly to provide corresponding points of connection, at least three weights between the two members, two pairs of links for each weight, one pair being pivoted to the weight and the first member, the other pair being pivoted to the weight and the second member, the links of each pair, with the weight and the respective member, providing a parallelogram linkage that holds the second member in parallelism to the first member as the weights move radially.
